FIG. 1 is a top perspective view showing the new design for a window film attachment applicator tool;
FIG. 2 is a first side view thereof;
FIG. 3 is a second side view thereof;
FIG. 4 is a third side view thereof;
FIG. 5 is a top view thereof;
FIG. 6 is a bottom view thereof;
FIG. 7 is a bottom perspective view thereof; and,
FIG. 8 is a cross-sectional view thereof, taken along line 8-8 in FIG. 5. Only one cross-sectional view is presented because both left and right cross-sectional views are identical with respect to the vertical plane chosen in this view.
The broken lines depict portions of the window film attachment applicator tool in which the design is embodied that are not considered part of the claimed design.
